UNITED STATES PATENT OFFICE.

WILLIAM F. TRAUB, OF CHICAGO, ILLINOIS.

GAS RANGE.

Application filed June 19, 1922. Serial No. 569,285.

This invention relates to gas burners, and has for its object to provide a new and improved device of this description by means of which a greater efficiency is secured in the consumption of gas. The invention has as another object to secure a greater efficiency in the utilization of the heat generally. The invention has other objects which are more particularly pointed out in the following description. Referring now to the drawings

Fig. 1 is a plan view of the burners with parts broken away;

Fig. 2 is a sectional view taken on line 2—2 of Fig. 1;

Fig. 3 is a side view of Fig. 1;

Fig. 4 is a bottom view of Fig. 1;

Like numerals refer to like parts throughout the several figures.

In the drawings I have shown the particular construction of the burners. In this construction each burner is provided with a central tube 9. The tube 9 of the burners is surrounded by an outer tube 4^a which is connected with a source of gas supply, such as the burner supply pipe 8. The tube 9 extends through the connection of the tube 4^a with the source of gas supply, and is open both at its lower and its upper ends as clearly shown in Fig. 7 so that air may pass therethrough. The tubes 4^a pass up through the part 10, and there are openings 10^a in this part around each tube 4^a so that when the burner is burning, air passes up through the openings 10^a to the flame. It will thus be seen that the gas passes into the space between the tubes 9 and 4^a to its discharge point and that upon each side of the gas discharge opening, air is also discharged, the air on one side coming through the tube 9, and the air on the other side coming through the opening 10. This construction greatly decreases the amount of gas required and increases the efficiency of the range.

Heat from the burners passes through the passageways 2^a and 3^a at the top of the oven and then passes along down the ends of the ovens through the passageways 2^b and 3^b and then along the bottom of the oven through the passageways 2^c and 3^c and then passes into the

passageways 2^d and 3^d at the back of the oven, as shown in Figs. 2, 3 and 4, and then to the chimney 11. The passageways 2^e and 3^e are preferably provided with baffle plates 2^e and 3^e to properly distribute the heat. Beneath the ovens are passageways 12 and 12^a which admit air to the chamber 13 containing the burners. The passageways 12 and 12^a preferably have thin conducting walls so that the heat from the gases in the passageways 2^e and 3^e heat this incoming air, thus causing the air which is supplied to the burners 4 to be heated before being supplied to the burners, and this heated air also tends to heat the gas passing to the burners through the tubes 7 and 8. This construction increases the efficiency of the burner.

I claim:

1. A burner having a pipe open at both ends through which air passes, a second pipe surrounding the first pipe and spaced therefrom, the space between the two pipes closed at one end and open at the other end, a perforated plate through which the open ends of both of said pipes project, the opening in the plate being larger than the outer pipe so as to leave an air space surrounding it through which air passes when the burner is operated, and means for admitting gas in the space between the two pipes, the ends of said pipes being substantially flush with the top of said perforated plate.

2. A burner comprising a horizontal pipe having separated openings extending laterally therethrough, projecting pipes connected with the horizontal pipe and surrounding the openings, open air pipes extending through said openings in said horizontal pipe, a perforated plate into which the ends of said projecting pipes and open air pipes are received, the perforations in the plate being larger than the projecting pipes so as to provide a space surrounding them through which air may pass, and means for admitting gas to said horizontal pipe.

Signed at Chicago, county of Cook, and State of Illinois, this 2nd day of June, 1922.

WILLIAM F. TRAUB.
